RAILWAY TRAFFIC CONTROLLING
SYSTEMSedgwick N. Wight, Rochester, N. Y., assignor to
General Railway Signal Company, Rochester, N. Y.Application November 1, 1929, Serial No. 404,022
Renewed September 20, 1932

23 Claims. (Cl. 246—160)

This invention relates to approach locking circuits and devices for remote controlled power-operated switches, and more particularly to means for releasing the approach locking.

5 For reasons well known to those skilled in the art, it is important that the operation of a power-operated switch, controlled from a distant point, should be safe-guarded so that it cannot be operated with a train approaching the switch at 10 such a time and under such conditions that the switch might be unlocked or in mid-stroke when reached by the train. Such a scheme for approach locking protection is shown and described in my prior application, Ser. No. 120,423, filed July 15 3, 1926. In such an approach locking system, and others of a similar type, it is desirable to make provision for energizing a relay or similar electro-responsive means, upon movement of a train by a switch; and while this may be done by utilizing 20 the shunting of the detector track circuit at the switch, as shown in my above mentioned application, it may happen that the detector track relay is improperly shunted for some reason when a train is approaching and will cause an improper 25 release of the approach locking.

In accordance with the present invention, it is proposed to make the release of the approach locking dependent upon a simultaneous shunting of two adjacent track circuits, which are both 30 shunted at the same time during normal train movements by the switch, so that the accidental or improper shunting of one of these track circuits will not release the approach locking.

35 Various characteristic features, objects, and advantages of the invention will be in part apparent, and in part pointed out, as the description progresses.

40 The accompanying drawing shows in a simplified and diagrammatic form one specific embodiment of the invention, the parts and circuits being shown more with the object of making it easy to understand the principles and mode of operation of the invention, than with the purpose of illustrating the detail construction of 45 the various devices involved, and the circuit organization preferably employed in practice.

45 For the purposes of illustration, but not by way of limitation, the invention has been shown as applied to power-operated switches employed 50 in a centralized control or train dispatching system, and particularly with respect to the switch at one end of a passing siding PS. The approach locking circuits embodying the invention have been illustrated for the switch SW at the east or 55 right-hand end of the passing siding PS. This

switch is assumed to be operated by a suitable switch machine, preferably of the electrical type, such as shown and described in the patent to W. K. Howe, No. 1,466,903, dated September 4, 1923. This switch machine (not shown) may be controlled in any suitable manner by the distant operator, such as disclosed, for example, in my prior application above mentioned; and since the specific means employed for the control of this switch machine, while forming part of the complete system embodying the invention, is not material to the approach locking means constituting the invention, such control circuits and devices for the switch machine have not been shown. It is also assumed that the switch SW 15 will be provided with suitable point detector contacts, such as shown, for example, in the patent to Chas. S. Bushnell, No. 1,517,236, dated November 25, 1924, which are operated automatically in accordance with the position and 20 locked condition of the switch points as operated by the switch machine. Such point detector contacts, which may be simple switch circuit controller contacts, are shown diagrammatically as comprising contact members 20 25 and 21, movable from the normal position shown to a reverse position, thereby opening and closing circuits in a manner which will be evident from the drawing.

For the purposes of this invention, the insulating joints 15, providing the usual detector track circuit at the switch SW, are so located and arranged as to provide two separate track circuits having track relays 9T and 9AT. With the switch SW in the normal position, that is, set 35 for the main track, the track relay 9T is shunted by a passing train; whereas with the switch SW in a reverse or take-siding position, the track relays 9T and 9AT are successively shunted by a train moving onto or off of the siding. 40

The stretch of track on both sides of the switch SW under consideration is divided into track sections, each provided with a source of current, designated B and a track relay. These track sections are designated 6—12 inclusive, and their 45 corresponding track relays 6T to 12T.

West-bound traffic (from right to left) over the switch SW is governed by signals 1 and 1A; and east-bound traffic by the signals 2 and 2A. Similarly, traffic over the switch at the other end of 50 the passing siding PS is governed by signals 3—3A and 4—4A. Signal 5 governs west-bound traffic approaching this switch SW. These signals may be of any suitable type, but for simplicity, are assumed to be semaphore signals. It is also as- 55

sumed that these signals will be automatically controlled by track circuits in accordance with the well-known absolute-permissive-block signal system, subject to manual control by the distant operator or dispatcher, in a manner described in my prior application above mentioned. For simplicity, in explanation, it is assumed that the signals 1—1A and 2—2A will be controlled by a signal control relay ZS of the neutral-polar type, energized over line wires 16 and 17 from a battery 18 at the dispatcher's office, in accordance with the position of the contacts of the control lever L, in a manner as will be evident from the drawing without detail explanation.

15 The system of approach locking constituting the invention, consists of suitable means for controlling the energization of a lock relay LR, having contact fingers or armatures 18 and 19, which controls the operation of the switch machine (not shown) in some suitable manner, as by opening the control or operating circuits for the switch machine at the front contact 19 of lock relay LR, when it is de-energized. In other words, in considering the nature of this invention and its 20 practical application, it should be understood that the lock relay LR, when energized, permits power operation of the switch SW, providing the detector track circuits are unoccupied, but if de-energized, prevents such operation.

30 The lock relay LR is controlled by approach relays AW and AE and the detector track relays 9T and 9AT, and is dependent upon the position of the signals 1—1A and 2—2A, and the signal control relay ZS, all in a manner about to be explained in discussing the operation of the system.

Operation.—Considering first the signal control circuits, it will be noted that the west-bound signal 1 or 1A may be cleared, dependent upon the position of the switch SW and the point detector contact 21, over a circuit including wire 24, front contact 25 of line relay 1H, wire 26, polar contact 27 of the signal control relay ZS to the left, wire 28, and neutral contact 29 of the relay ZS. The line relay 1H is controlled by a circuit (not shown) controlled by the track relays at the west of the signal 1—1A and between these signals and the next west-bound signal 3—3A, as more fully shown in my prior Patent No. 1,294,736, dated Feb. 18, 1919.

50 Similarly, the east-bound signals 2 and 2A are selectively controlled by the point detector contact 21, the line relay 2H, and the polar and neutral contacts 27 and 29 of the signal control relay ZS. It will be evident that the operator by 55 positioning the lever L may energize the relay ZS with current of either polarity, and will thereby cause clearing of either the east-bound or west-bound signals, dependent upon the position of the switch, and providing no trains are present de-energizing the line relays 1H and 2H. With 60 the relay ZS energized toward the right the signals 2 and 2A may be energized through the following circuits:—beginning at the terminal (+), front contact 29 of the relay ZS, wire 28, polar contact 27 toward the right, wire 80, front contact 81 of the relay 2H (assuming traffic conditions in advance to be clear), wire 82, contact 20, wire 83 and mechanism of signal 2 or wire 84 and mechanism of signal 2A depending upon whether 65 the track switch SW respectively assumes the main track or side track positions, and back to the other terminal (—) of a suitable battery.

70 The east approach relay AE is energized by a circuit which may be traced from B (+), through 75 the front contact 30 of track relay 12T, wire 31,

front contact 32 of track relay 11T, wire 33, front contact 34 of track relay 10T, wire 35, relay AE to C (indicating a common return connection to the other terminals of the battery).

The west approach relay AW may be energized by either of two circuits, one of which may be traced from B (+) through the front contact 36 of the track relay 6T, wire 37, front contact 38 of track relay 7T, wires 39 and 40, front contact 41 of track relay 8T, wire 42, relay AW to C, and 10 the other of which may be traced from B (+) through the point detector or switch circuit controller contact 43, closed with the switch reverse, wires 44 and 40, then through the front contact 41 of the track relay 8T, the same as in the other 15 circuit.

From these circuits just traced it can be seen that a west-bound train approaching the switch SW from the east, and closer to the switch than one track section in the rear of signal 5, deenergizes the approach relay AE. An east-bound train, approaching the switch SW from the west, and closer to it than one track section in the rear of the signals 4—4A deenergizes the relay AW, unless the switch at the west end of the passing siding PS is in the reverse position, whereupon the relay AW is de-energized only if there is a train on the track section 8.

Assuming that there is no train approaching the switch SW in either direction, so that the relays AW and AE are energized, and that the signals 1, 1A, 2, 2A are in the stop position, the lock relay LR is energized by a circuit which may be traced from (+), front contact 46 of the relay AW, wire 47, front contact 48 of relay AE, 35 wires 49 and 50, relay LR, wire 51, circuit controller 52 of signal 1A closed in the stop position, wire 53, circuit controller 54 of signal 1, wire 55, circuit controller 56 of signal 2A, wire 57, circuit controller 58 of the signal 2 to (—).

40 The relay LR thus once energized is maintained energized by a stick circuit from (+), through its front contact 18, wires 59 and 50, relay LR and thence to (—) through the circuit controllers 52, 54, 56 and 58 of the signals 1—1A, 45 2 and 2A. Thus, while the signals governing traffic over switch SW are held at stop, a train approaching from either direction does not de-energize the relay LR, which is then maintained energized by its stick circuit; and the operator 50 may at any time operate the switch SW. It will be readily appreciated that this arrangement affords the desired safety, since with the signals 1—1A and 2—2A at stop, any train approaching will receive a caution or approach restrictive indication at the signals 4 and 5 in accordance with established A. P. B. practice, and will slow down and stop before reaching the switch SW, so that the switch may be properly and safely operated while the train is approaching.

60 Whenever any one of the signals 1—1A, or 2—2A is cleared, the lock relay LR is de-energized, and any operation of the switch SW is prevented, until this relay LR is again energized. If there is no train approaching so as to cause 65 de-energization of the relays AW and AE, the lock relay LR may be energized as soon as the signal cleared assumes its stop position. Consequently, if the operator should set the switch SW in one position or the other, and should clear 70 the corresponding east or west-bound signals, in anticipation of a certain train movement, and then should change his mind, he is able to re-energize the relay LR and operate the switch by putting his lever L on center to de-energize the 75

signal control relay ZS and put to stop the signal that he has cleared, provided that no train has in the meantime come within the approach locking limits and caused de-energization of either of the relays AE or AW.

Considering now the case of a normal train movement over the switch SW, and the manner in which the relay LR is re-energized, or in other words, how the approach locking is released, and assuming a west-bound train movement on the main track, the relay LR is re-energized as soon as this west-bound train shunts the track relays 9T and 8T by a circuit which may be traced as follows:—starting at (+), through the back contact 60 of the track relay 9T, wires 61 and 62, back contact 63 of relay AW, wire 64, polar contact 65 of relay ZS to the left, wire 66, point detector contact 22 normal, wires 67, 68 and 58, relay LR and thence over wire 51 through the circuit controllers of the signals 1, 1A, 2 and 2A, the signal 1 assuming its stop position when the train shunts the track relay 9T.

Assuming an east-bound train movement on the main track, the operator or dispatcher positions the lever L to energize the signal control relay ZS with a polarity to clear the signal 2; that is, as shown, the polar contact 65 of this relay ZS assumes the right-hand position. As this east-bound train passes over the detector track circuit 9 and enters the track section 10, de-energizing the track relay 10T and consequently the approach relay AE, a pick-up circuit for re-energizing the lock relay LR is established, the signal 2 being caused to automatically assume its stop position by the entry of the train into the detector track circuit 9, this because the signal 2 is controlled by the home relay 2H which relay in turn has included in its energizing circuit a front contact (not shown) of the relay 9T, said circuit being traced as follows:— starting at (+), through the back contact 60 of the detector track relay 9T, wires 61 and 70, back contact 71 of the relay AE, wire 72, polar contact 65 in the right-hand position as shown, wire 66, point detector contact 22, wires 67, 68 and 58, relay LR, wire 51, and thence through the signal circuit controllers 52, 54, 56 and 58 to (—).

Considering now a west-bound train movement onto the siding PS, that is, over the switch SW in its reverse position, in this case, the release locking circuit for re-energizing the relay L starts at (+), through the back contact 73 of the track relay 9AT, wire 74, back contact 75 of the track relay 9T, wire 76, point detector contact 22 in the reverse position, wires 77, 68 and 58, relay LR and wire 51 through the signal circuit controllers to negative, in the same way as the other circuits above traced. In practice the points of the switch SW are bonded to the rails of the track circuit containing track relay 9T, so that even the shortest railway car passing into the side track will simultaneously de-energize the track relays 9T and 9AT, from which it is apparent that each entrance of a train into the side track will result in simultaneous de-energization of the relays 9T and 9AT.

An east-bound train, moving off of the siding onto the main track, picks up the relay LR in the same way by the simultaneous de-energization of the track relays 9T and 9AT.

As already noted, the track relays 9T and 9AT are connected to separate track circuits one including the track rails of the main track opposite the switch SW, and the other track rails of the end of the passing siding, up to or beyond

the fouling point, the arrangement of insulated joints, the track batteries, and relay connections for such an arrangement of track circuits being well known and familiar to those skilled in the art.

It will be noted that the release of the approach locking is dependent upon the simultaneous shunting of the two track relays, as 9T and 8T; and this is one of the important characteristic features of the invention. Assuming that the re-energization of the relay LR in the case of a west-bound train on the main track, above just explained, were dependent merely upon the shunting of the detector track relay 9T, if the west-bound train had passed the signal 5 and was approaching the switch SW at high speed, the detector track relay 9T might be accidentally or improperly shunted for some reason, putting the signal 1 to stop and energizing the relay LR to permit operation of the switch SW in the face of the train approaching at high speed. While such improper shunting of the track relay 9T is remote, there are special circumstances under which this may occur, perhaps due to a temporary track circuit failure, careless manipulation by a maintainer, or the like. Such shunting of the detector track relay 9T, under the conditions just described, would tend to bring about an unsafe condition, not only because the approach locking would be improperly released, but also because the dispatcher, thinking that the indication resulting from the shunting of the track relay 9T signified the arrival of the expected train, would be expected to operate the switch control lever. By making the re-energization of the lock relay LR dependent upon the simultaneous shunting of two track relays, in accordance with this invention, it will be evident that the possibility of such dangerous condition is greatly minimized, if not entirely eliminated, since it is most unlikely that two track circuits will fail at the same time or be carelessly shunted by a maintainer.

It will be noted that two different track relays are employed for releasing the approach locking in the case of a west-bound train on the main track, an east-bound train on the main track, and a train entering or leaving siding, namely track relays 8T and 9T, 10T and 9T, and 9AT and 9T, respectively, and it will be observed that the two track relays effective to release the approach locking are selected by the polar contact 65 of the signal control relay ZS and the position of the point detector contact 22. In other words, the position of the switch points (contact 22) and the direction of train movement (polar contact 65 of relay ZS) determine which two track relays are effective to cause re-energization of the lock relay LR. After a little consideration, it will be evident that such selection is necessary to obtain the desired protection in the release of the approach locking. For example, if the release of the approach locking were dependent upon track relays 9T and 10T, for trains moving in either direction, the detector track relay 9T might be improperly shunted with a west-bound train approaching at high speed and entering the track section 10, thereby causing an improper release of the approach locking. Such contingency is avoided by making the release of the approach locking dependent upon the detector track relay 9T and the track relay of the track section in advance thereof, depending upon the direction of the train movement, so that there is no release unless the approaching train has passed

over the detector track section 9, which of course does not occur unless one of the signals governing traffic over the switch SW is in the clear position, and opposing train movements are 5 blocked.

5 In the case of a train movement onto the siding, since the siding is not usually equipped with track circuits, it is not possible to obtain the co-operation of the detector track relay 9T, and a 10 track relay of a track section next in advance thereof, to provide the release for the approach locking, so that the extra track circuit, with its track relay 9AT is provided at the switch; and these same two track relays 9T and 9AT are 15 employed for releasing the approach locking by a train movement off of the siding.

10 The approach relay AW is controlled by the contact 43 of the switch at the other or west end of the siding PS, in order that an east-bound train taking the siding will not cause approach locking of the switch SW, it being permissible for the operator to retain control of the switch SW in such a case, since movements on the siding are low speed movements. For a high-speed east-bound movement, however, the control for the relay AW should extend to at least one track section in the rear of the signal 4—4A, to provide the proper approach locking limits; and if it were not for the contact 43 and its associated shunt 20 circuit, an east-bound train entering the siding, would lock up the switch SW, and during its normal movement would not release this approach locking, with the result of unnecessarily restricting control of the switch by the operator.

25 35 While I have shown and described one specific embodiment of the invention applied to a switch for a passing siding on a railroad equipped with a centralized control or dispatching system, it should be understood that the invention is not limited to this particular application, or to the 40 particular construction and arrangement of parts and circuits shown and described, various additions, modifications, and adaptations in the specific embodiment of the invention disclosed 45 being possible, without departing from the invention.

What I claim is:—

1. In a system of approach locking for power-operated switches, the combination with a lock 50 stick relay which must be energized to permit power operation of a railway track switch, of a pick-up circuit for said stick relay closed only upon simultaneous shunting of two different but adjacent track circuits.

55 2. In a system of approach locking, the combination with a power-operated switch, of signals for governing traffic over said switch, a lock relay which must be energized to permit power operation of a railway track switch, and a particular energizing circuit for said relay closed only when said signals indicate stop and two different track circuits adjacent the switch are simultaneously shunted.

60 65 3. In a system of the character described, a power-operated switch over which traffic may move in opposite directions, a lock relay controlling the operation of said switch, a detector track circuit, track circuits adjacent to said detector track circuit on each side thereof, two energizing circuits for said lock relay each closed when the detector track circuit and an adjacent track circuit in advance thereof are closed, and means depending upon the direction of train 70 movement toward the switch for rendering one

or the other of said circuits effective to control said lock relay.

4. In a system of the character described, a power-operated track switch, two track circuits at the switch, one in the main track and the 5 other in the turn-out track, a lock relay which must be energized to permit power operation of said switch, an energizing circuit for said relay closed only when said two track circuits are concurrently shunted, and means for rendering said 10 circuit effective to energize said relay when the switch is in the reverse position.

5. An approach locking system for power-operated switches over which trains may move in either direction comprising, a lock relay, an en- 15 ergizing circuit for said relay, and means dependent upon the position of the switch and the direction of train movement over the switch for closing said circuit and effective only when two adjacent track circuits associated with such 20 switch are simultaneously shunted.

6. A system for releasing approach locking of the character described comprising, in combination with a detector track circuit and other track circuits adjacent thereto, a lock relay having a 25 plurality of energizing circuits, each of said circuits being dependent upon simultaneous shunting of said detector track circuit and a different one of said adjacent track circuits, and means depending upon the direction of train movement 30 over the switch and the position of said switch for selecting the circuit effective to energize said relay.

7. In a system of approach locking for power-operated switch machines, the combination with 35 a lock relay of the stick type which must be energized to permit operation of such power-operated switch, signals associated with said switch, a pick-up circuit for said relay closed only if said signals are at stop and two different 40 track circuits adjacent said switch are simultaneously shunted, and a stick circuit for said relay including its own stick contact and closed if said signals are at stop.

8. In a system of approach locking for power- 45 operated switch machines, the combination with a lock relay of the stick type which must be energized to permit operation of such power-operated switch, a detector track circuit associated with said switch, a track circuit in advance 50 and in the rear of said detector track circuit, and two pick-up circuits for said lock relay one including contacts closed when said detector track circuit and the track circuit in advance are simultaneously shunted and the other including contacts closed if said detector track circuit and the track circuit in the rear are simultaneously shunted.

9. In a system of approach locking for power-operated switch machines, the combination with 60 a lock relay of the stick type which must be energized to permit operation of such power-operated switch, signals associated with said track switch, an approach section, an approach relay having an energizing circuit closed when 65 said approach section is unoccupied, and two pick-up circuits for said lock relay one including signal contacts closed when said signals are at stop and a front contact of said approach relay in series and the other including said signal contacts closed only when two different track circuits adjacent said switch are simultaneously shunted.

10. In a system of approach locking for power-operated switch machines, the combination with 70

a lock relay of the stick type which must be energized to permit operation of such power-operated switch, signals associated with said track switch, an approach section, an approach 5 relay having an energizing circuit closed when said approach section is unoccupied, two pick-up circuits for said lock relay one including signal contacts closed when said signals are at stop and a front contact of said approach relay in series and the other including said signal contacts and contacts closed when two different track circuits adjacent said switch are simultaneously shunted, and means for selecting said pick-up circuits in accordance with the position 10 15 said switch is assuming.

11. In a system of approach locking for power-operated switch machines, the combination with a lock relay of the stick type which must be energized to permit operation of such power-operated switch, signals associated with said switch, a pick-up circuit for said relay closed only if said signals are at stop and two different track circuits adjacent said switch are simultaneously shunted, a stick circuit for said relay including 20 25 its own stick contact and contacts closed if said signals are at stop, and means for rendering said pick-up circuit effective only if said switch assumes a particular position.

12. In combination, a railway track switch, signals associated with said switch for governing traffic in opposite directions over said switch, a lock relay which must be energized to permit operation of said switch from a remote point, two approach sections one on each side of said switch, 30 35 a control relay for controlling the clearing of said signals and permitting clearing of a signal for one direction of traffic at one time only, and an energizing circuit for said lock relay closed only if the approach section for the opposite signal 40 45 from the one selected by said control relay is occupied and including a contact of said control relay closed when said one signal is selected for clearing.

13. In combination, a railway track switch, signals associated with said switch for governing traffic in opposite directions over said switch, a lock relay which must be energized to permit operation of said switch from a remote point, two approach sections one on each side of said switch, 50 55 a lever for clearing one of said signals, and an energizing circuit for said lock relay closed if said lever is in a position to clear said one signal and the approach section in advance of said one signal is occupied by a train.

14. In combination, a railway track switch, signals associated with said switch for governing traffic in opposite directions over said switch, a lock relay which must be energized to permit operation of said switch from a remote point, three approach sections one in each track leading to said switch, a lever for selecting signals for governing traffic in one direction or the other over said switch, contacts associated with said track switch for selecting the proper route signal of the signals selected by said lever, and a circuit for said lock relay closed if the approach section in advance of the selected route signal is occupied.

15. In combination, a railway system having a passing siding, a track switch at each end of said passing siding, a lock relay for one of said track switches which permits operation of such one switch from a remote point only if said lock relay is energized, and means for controlling said lock relay by circuits including contacts respec-

tively reflecting the positions of the two track switches.

16. In combination, a railway system including a traffic route, a stick relay which allows the establishment of said route if and only if said stick relay is energized, two adjacent track circuited track sections in another route having a portion in common with said first mentioned route each section including a normally energized track relay, and a pick-up circuit for said stick 10 15 relay including two contacts in series one of which is closed upon occupancy of one of said track sections and the other of which is closed upon occupancy of the other of said track sections.

17. In combination, a track switch, a railway system including a traffic route, a stick relay which allows the establishment of said route if and only if said stick relay is energized, two adjacent track circuited track sections in another 20 route having a portion in common with said first mentioned route each section including a normally energized track relay, and a pick-up circuit for said stick relay including two contacts in series one of which is closed upon occupancy 25 of one of said track sections and the other of which is closed upon occupancy of the other of said track section and also including a contact closed only if said track switch assumes a particular position.

18. In combination, a railway signal, an approach track circuit for said signal including a track relay, a second and a third track circuit each of which includes a track relay, an approach locking relay, a circuit for said approach 30 35 locking relay controlled by said approach track relay, and a second circuit for said approach locking relay including a back contact of said second track relay in series with a back contact of said third track relay and controlled by said 40 signal.

19. In combination, a railway signal, an approach track circuit for said signal including a track relay, a second and a third track circuit each of which includes a track relay, an approach 45 locking stick relay, a pick-up circuit for said approach locking relay controlled by said approach track relay, a second pick-up circuit for said approach locking relay including a back contact of said second track relay in series with a back 50 contact of said third track relay, and a stick circuit for said approach locking relay controlled by said signal.

20. In combination, a section of railway track containing a switch, an approach section adjoining 55 said switch section, a second approach section adjoining said switch section, a signal for governing traffic movements over said switch, an approach locking relay, a circuit controlled by traffic conditions in said first approach section 60 and including the winding of said relay for controlling said relay, a second circuit controlled jointly by traffic conditions in said switch section and traffic conditions in said second approach section and including the winding of said relay 65 for controlling said relay, a third circuit controlled by said signal for controlling said relay, and means controlled by said relay for controlling said switch.

21. In a system of the character described, a 70 power-operated track switch, two track circuits at the switch one in the main track and the other in the turn-out track, a lock relay which must be energized to permit power operation of said track switch, an energizing circuit for said lock relay 75

closed only when said two track circuits are shunted concurrently, and means for rendering said circuit effective to energize said lock relay only when the switch is in the turn-out position.

- 5 22. In a system of the character described, a power-operated track switch, a detector track circuit associated with said track switch, another track circuit in a track section adjacent said detector track circuit, a stick lock relay for 10 when deenergized preventing power operation of said track switch, a pick-up circuit for said stick relay including contacts closed only if both of said track circuits are simultaneously occupied, and a stick circuit for said stick relay closed only 15 if a signal for governing movement of traffic over said switch is at stop.

23. In combination, a passing siding of a rail-

way system and having a track switch at each end thereof, a switch machine for power operating one of said track switches, a lock relay which must be energized to permit power operation of said one track switch, two approach sections one reflecting track occupancy in the single track section facing the points of said one track switch and the other approach section reflecting track occupancy of the main track of said passing siding, means for extending said other approach section beyond the limits of said passing siding and into the single track section facing the points of the other track switch when said other track switch assumes the main track position, and an energizing circuit for said lock relay closed only 15 if both of said approach sections are unoccupied.

SEDGWICK N. WIGHT.
